UNITED STATES PATENT OFFICE.

PHILIPPE DE CLAMECY, OF BOSTON, MASSACHUSETTS, ASSIGNOR TO REMINGTON TYPEWRITER COMPANY, OF ILION, NEW YORK, A CORPORATION OF NEW YORK.

TYPEWRITING MACHINE.

1,423,311.

Specification of Letters Patent.

Patented July 18, 1922.

Application filed January 21, 1920. Serial No. 352,927.

To all whom it may concern:

Be it known that I, PHILIPPE DE CLAMECY, citizen of the United States, and resident of Jamaica Plain, Boston, in the county of 5 Suffolk and State of Massachusetts, have invented certain new and useful Improvements in Typewriting Machines, of which the following is a specification.

My invention relates to typewriting machines, and more particularly to a so-called portable type of machine which may be readily contracted into compact form in order that it may be conveniently carried or transported.

15 The main object of my invention, generally stated, is to provide a simple and efficient machine of the character specified, and one in which parts may be readily contracted from their normal position of use to reduce 20 the cubical dimensions of the machine.

A further object of the invention is to provide a machine of the character specified in which the parts when contracted may be fully protected from injury and enclosed 25 within a frame or case and may be thus carried or shipped.

To the above and other ends which will hereinafter appear my invention consists in the features of construction, arrangements 30 of parts and combinations of devices set forth in the following specification and particularly pointed out in the appended claims.

In the accompanying drawings wherein like reference characters indicate corresponding parts in the various views,

Figure 1 is a central vertical fore and aft sectional view of one form of typewriting machine embodying my invention, the parts appearing in positions for use and only so 40 much of the machine being shown as may be necessary to arrive at an understanding of my invention.

Figure 2 is a vertical transverse sectional view of the same with parts omitted, the section being taken on the line $x-x$ of Fig. 1 and looking in the direction of the arrow at 45 said line.

Figure 3 is a fragmentary plan view of the machine, parts appearing in the expanded position, or in condition for use.

Figure 4 is a detail fragmentary transverse sectional view of the machine corresponding to Fig. 2 but showing the parts as they appear when the carriage has been in-

verted and lowered and is ready to be slid 55 or telescoped into the body of the machine.

Figure 5 is a side elevation of the machine, shown contracted and closed, ready for 60 transportation.

Figure 6 is a detached detail perspective view of the auxiliary or case shift frame on which the carriage and its support are mounted.

Figure 7 is a detail detached perspective 65 view of the carriage support.

Figure 8 is a fragmentary detail perspective view of the carriage frame.

Figure 9 is an enlarged detail sectional view of the locking bolt for the carriage support together with some of the associated parts.

For the purpose of the present invention any suitable printing instrumentalities may be employed, though I prefer to embody my 70 invention in a front strike typewriting machine in which there is a relative case shifting movement effected between the platen and the printing instrumentalities. Certain features of the present invention pertain to 75 case shifting means combined with features whereby the contraction of the machine may be effected.

What may be termed the main frame of the machine is preferably of the non-collapsible or non-folding type and comprises a base 1, fixed side plates 2, a rear fixed cross plate 3, and a front fixed cross plate 3^a. When the parts are in the contracted relationship, as shown in Fig. 5, all parts 80 of the machine are confined within the outline of this frame. In the present instance the dimensions of the main frame are not altered by an expansion of the machine or by a contraction thereof. The main frame 85 is adapted to enclose the machine at the bottom, at the rear, at both sides and to partly enclose it on the front side, as at 3^a, and when combined with a suitable cover, to entirely enclose the machine and constitute 90 a carrying case therefor.

In the present instance the cover 4 is in the nature of a flexible slat cover of the same general character as those employed in roll-top desks. This cover is jointed, or 105 hinged at one end, as at 5, to the upper edge of the rear cross plate 3 of the frame, and when not in use may hang down in the rear of the machine, as shown in Fig. 1.

The other end of the cover is provided with a catch 6 adapted to be received in a suitable lock 7 secured to the front plate 3^a of the frame. Suitable holding devices may 5 be employed to secure the cover against the edges of, and against displacement from, the frame. In the present instance each holding device 8 is in the nature of an angle-iron pivoted at 9 to a side plate of the frame, 10 and having a portion or flange 8^a which is adapted to overlap the cover and hold it securely in place on the frame. Each holding device may be perforated at 10 to receive a turn-button 10^a carried by the frame. 15 The holding devices may thus be locked in operative position. The frame may be provided with rubber feet 11 for supporting the machine, and may also be provided at the front end thereof with a handle 12 to 20 facilitate carrying the machine.

The printing instrumentalities illustrated in the present instance comprise a series of upwardly and rearwardly striking, segmentally arranged, type bars 13 pivoted on 25 a pivot wire 14, suitably supported and held on the main frame of the machine. The heel of each type bar is pivoted to a pull link 15 united at its forward end to a flexible connection 16 of wire or other suitable 30 material. Each wire 16 passes through an opening in a vertically disposed plate 17 secured to or forming part of the main frame. This plate carries a series of grooved guide rollers 18, each of which coacts with 35 and supports a wire 16. Each wire passes from its roller 18 under a grooved guide roller 19 on a suitably guided stem 20 of the companion printing key 21. The forward end of each wire is anchored to the 40 frame of the machine at 22 beneath a keyboard plate 23. A coiled expansion spring 24 surrounds each wire 16 and bears at one end against the plate 17, and at its opposite end against a collar 25. This spring is effective to return the parts of the associated 45 type action to normal position.

The escapement mechanism for the carriage, and the means for controlling the same from the printing keys are not shown, 50 but may be understood to be of any suitable character, and to be controlled also from a space key or bar 26 operative on a flexible connection 27 similar to the connections from the printing keys to the type bars. 55

Contained within the main frame and confined within the outlines thereof is an auxiliary frame, designated as a whole by the reference numeral 28 and shown detached in 60 Fig. 6. This frame is, generally speaking, rectangular in form and constitutes a support for the carriage in both the expanded and contracted position of the latter, and also constitutes a shift frame by which the 65 carriage may receive a bodily case shifting

movement as will presently appear. From certain aspects of my invention the means employed for mounting the auxiliary frame 28 in the main frame for case shift movement, and the means for effecting such case 70 shift movement, may be of any suitable character. As shown in the present instance the skeletonized or cage-like frame 28 comprises upright supporting and guide members 29, 30, 31 and 32, each of which is of 75 dove-tail formation in cross section for reception in correspondingly grooved guide ways 33, 34, 35, 36 respectively on the main frame. The upright members are connected at their upper ends by inwardly extending arms to a longitudinally extending, rectangular, supporting section formed of parallel side members or plates 37, united by cross braces 38, 39 and 40. The lower ends of the uprights 29, 30, are connected to a 80 cross head 41, from which a longitudinally extending member 42 projects, the opposite end of the member 42 connecting with the upright 32. A laterally extending brace 43 extends from the member 42 and connects 85 with the lower end of the upright 31. It will be observed that the parallel side members 37 are connected to the upper ends of the uprights 29, 30, and 31 by off-set extensions 44, so that these uprights are spaced 90 apart from the members 37. Below the cross-braces 38 and 39, and between the uprights 29 and 30 and the plates 37 an unobstructed channel, passage or opening extends 95 from one end to the other of the frame 28. 100 The construction of this frame is such that the carriage together with its support, may be inverted, lowered and moved endwise on or telescoped into the frame 28 as will presently appear. A longitudinally extending 105 grooved track 45 is formed on each of the members 37, and each track extends upward at one end thereof, as indicated at 46, and terminates in a reentrant portion that forms a seat 47 above the upright portion 46 of the 110 track. Both tracks are formed in a like manner, and each is adapted to receive an inwardly projecting pin 48 adapted to turn and slide thereon. Each pin extends from a depending lug 49 on a carriage supporting 115 member, designated as a whole by the reference numeral 50 and which is shown detached in Fig. 7. This carriage support is of a length which corresponds substantially to the length of the frame 28, and also corresponds substantially to the width of the latter between the supporting flanges 51 thereon. The carriage support 50 is formed with supporting flanges 52 and 53 which, when the support is in operative position, 120 rest upon the flanges 51 of the frame 28, and the latter thus forms a support for the member 50. I prefer to employ depending positioning lugs 54 on the carriage support, 125 which lugs are adapted to be received be- 130

tween and coact with the side plates 37 of the frame 28, and to hold the carriage support against lateral, or fore and aft, displacement from the frame 28. A depending 5 lug 55 projects from the carriage support 50 at the end thereof opposite that which carries the pins 48. This lug is perforated at 56 to receive the end 57 of a spring-pressed bolt 58, shown in detail in Fig. 9. The stem 10 59 of this bolt passes through an opening in one end of a sleeve 60 secured to the front plate 37 of the frame 28. The stem 59 is surrounded by a coiled expansion spring 61 which is contained within the sleeve 60 15 and bears at one end against an end wall of the latter, and at its opposite end against the head 57 of the bolt. The spring tends to force the bolt to locking position indicated in Fig. 9 where it is seated in the 20 opening 56 of the lug 55 on the carriage support and prevents the latter from being turned on the pins 48, or from moving endwise, thus locking the pins 48 in their seats 47.

25 A depending bracket arm 62 on the carriage support carries a stub shaft or spindle 62^a which constitutes a support for a spring drum 63. This spring drum has one end of a cord 64 attached thereto, the opposite end 30 of said cord extending through an opening in an end plate 65 of the carriage and provided with a collar, head or abutment 66. The cord 64, in extending from its spring 35 drum 63 to the carriage, passes over a grooved guide pulley 67 which is carried by the carriage support 50 adjacent to the opening therein through which the cord 64 passes. The carriage support 50 is formed with outwardly extending ribs 68, which extend longitudinally thereof throughout its length 40 and form tracks that are received within corresponding grooves 69 in the carriage rails 70. These rails are united by the end plates 65 of the carriage to constitute a frame, as shown in Fig. 8, for supporting a 45 cylindrical platen 71.

Any suitable paper feed mechanism may be employed to coact with the platen, paper feed rollers 72 being shown in the present 50 instance co-operating with the platen and extending through openings in a combined paper table and apron 73. Any suitable means are employed to limit the travel of the carriage on its support 50, and as hereinbefore pointed out, to control the carriage in its step by step feed movements under control of the printing and space keys.

It will be observed that when the parts are in the expanded or operative position 60 ready for use, as indicated in Figs. 1, 2 and 3 the carriage is supported above the top of the main frame to travel along the carriage support 50 from side to side of the machine over the auxiliary frame 28 and the main 65 frame and beyond the sides of the latter. At

this time the pins 48 are received in the seats 47 and are firmly held against displacement therefrom by the locking bolt 58, which at this time engages the depending lug 55 on the carriage support and locks it firmly to 70 the auxiliary frame 28. The carriage support 50 and the auxiliary frame 28 at this time are in effect one part.

In order that a relative case shift movement between the platen and printing instruments may be effected I have provided, in the present instance, for shifting the frame 28 bodily and thereby effecting a bodily case shift movement of the carriage. Thus it will be observed I have shown three types, 75 *a*, *b* and *c* on each type bar. It may be assumed that the types *a* are lower case characters, types *b* are upper case characters or capital letters, and that the types *c* are figures. I have provided for a shift of the 80 platen to either one of two positions from the normal, depending on the operation of a "cap." shift key 74, or an operation of a "fig." shift key 75. These keys may be connected like the printing keys to suitable actuating devices for shifting the frame 28 and the parts carried thereby upwardly from the normal position. Thus it will be understood that the lower end of the frame 28 bears against the bottom plate 1 of the main 85 frame and is supported thereby. A rod 76 is connected at one end to the upright 32 of the frame 28, and at its opposite end to an upwardly extending lug 77 on the member 42, and is thus fixed to the frame 28 and 90 maintained spaced apart from the member 42 thereof. An angular lever 78 is pivoted at 95 79 to a lug or support 80 which projects upwardly from the bottom plate 1 of the main frame. The rearwardly extending arm 100 105 of this lever is slotted at 81 to receive the rod 76, whereas the upwardly extending arm of this lever is perforated to receive a link 82 which extends freely therethrough, being provided at its rear end with a headed 110 portion 83. The link 82 is connected to a flexible connection or wire 84 like the printing keys, and is controlled in a like manner by its associated key 75. A set screw 85 is received in a tapped opening in a guide in 115 which the lower end of the stem of the key 75 works and limits the downward movement of the key stem, and the case shift devices controlled thereby.

The "cap." shift key 74 is connected in 120 a like manner to a bell crank lever 86 pivoted to a lug 87 and connected to the rod 76 like the bell crank lever 78. As indicated in Fig. 3 there may be two case shift keys 74 and 75 provided at each side of the machine, 125 the two "cap." shift keys, and the two "fig." shift keys being connected in a like manner to the rod 76 to effect an upward shift of the frame 28 to which said rod is connected. The frame 28 in its case shift movements, is 130

guided by the uprights 29, 30, 31 and 32 working in the grooved guides of the main frame in which said uprights are received and adapted to slide.

5 Should the operator desire to contract and enclose the machine it is merely necessary to pull the bolt 58 forward against the pressure of the spring 61 with the aid of the knurled head connected to the bolt 10 58. The effect of this is to free the bolt head 57 from the depending lug 55 on the carriage support 50. The carriage support may then be turned in a direction at right angles to the axis of the platen on the pins 15 48 in the seats 47 of the grooved track ways, so as to carry the carriage support out beyond the right-hand side of the main frame and invert the carriage support and effect a corresponding bodily movement of the 20 carriage mounted thereon. The carriage and its support may also be lowered by displacing the pins 48 along the upright terminal portions 46 of the grooved track ways to a position corresponding to that 25 shown in Fig. 4. In order, however, that the carriage and its support may assume this position I provide an opening in one of the side walls 2 of the frame through which the carriage and its support may be 30 inverted and lowered. I prefer to provide for this purpose a hinged door 88 pivoted at 89 to the rear cross plate, and adapted to swing from the closed position indicated in Figs. 3 and 5, where it practically constitutes a continuation with the associated side 35 plate 2 of the frame, to an open position such as is indicated in Fig. 4. The door may be secured in its closed position by a suitable pivoted latch 90 and one of the 40 holding devices 8 may be mounted in place on the door. When the door is open and the carriage and its support are inverted and lowered to the position indicated in Fig. 4 they may be moved together endwise or 45 telescoped into the body of the machine, the pins 48 at this time sliding longitudinally along the grooved tracks 45 in the frame 28. When the carriage and its support have been moved within the frame 28, 50 and contained wholly within the outer frame, the door 88 may be closed and locked, and the cover 4 may be drawn forward and locked and secured in position as hereinbefore described, thus entirely enclosing the 55 entire machine within the main frame, or case and materially reducing the height and the cubical dimensions of the machine.

From an inspection of Figs. 1 and 5 it will be seen that when the carriage and its 60 support 50 are inverted and telescoped into the machine through one side thereof the carriage and its support occupy a space directly beneath that which they occupied when in the operative position, or in position for use.

From what has been said it will be understood that the frame 28 constitutes a support for the carriage; that I have provided means whereby the latter may be inverted, lowered on and moved endwise or telescoped 70 into said support and into the main frame, and that in contracting the machine in this manner the carriage and its support receive a pivotal movement around an axis that lies in a plane extending transversely 75 of the axis of the platen, and also receive a sliding movement in the direction of the length and travel of the carriage.

Various changes may be made without departing from my invention and some features thereof may be employed without others.

What I claim as new and desire to secure by Letters Patent, is:—

1. In a typewriting machine, the combination of a carriage supporting frame, a carriage support mounted on said frame to turn around a center that extends fore and aft of the machine and also to slide on said frame, and a carriage mounted to travel 90 on said support.

2. In a typewriting machine, the combination of a carriage supporting frame mounted to receive a case shifting movement, a carriage support mounted on said frame to shift therewith and also to turn on said frame around a center that extends fore and aft of the machine and to slide thereon, and a carriage mounted to travel 100 on said support and to turn and slide there- with.

3. In a typewriting machine, the combination of a frame, a track on said frame, a carriage support mounted to turn and slide on said track from a position outside of to 105 a position inside the frame, and a carriage mounted on said support to travel thereon and also to partake of the turning and sliding movement of the support.

4. In a typewriting machine, the combination of a main fixed frame, an auxiliary frame received therein, a carriage support mounted for pivotal and sliding movement on said auxiliary frame and to move from a point above the auxiliary frame to a position within the main and auxiliary frames, and a carriage mounted to slide on said carriage support and to partake of the pivotal and sliding movement of the latter and move with it from a position of use and beyond 120 the outlines of the main frame to a position within the main and auxiliary frames and to be entirely confined within the outlines of the main frame.

5. In a typewriting machine, the combination of a main fixed frame, an auxiliary frame received therein, a carriage support mounted for pivotal and sliding movement on said auxiliary frame and to move from a point above the auxiliary frame to a posi- 130

tion within the main and auxiliary frames, a carriage mounted to slide on said carriage support and to partake of the pivotal and sliding movement of the latter and to move 5 with it from a position of use and beyond the outlines of the main frame to a position within the main and auxiliary frames and to be entirely confined within the outlines 10 of the main frame and means for effecting a cast shifting movement of said auxiliary frame and a corresponding movement of the carriage.

6. In a typewriting machine, the combination of a carriage, a support with a track 15 on which the carriage travels, a frame on which said support is adapted to be held fixed, and a track on said frame on which said support together with the carriage are adapted to move in the direction of the 20 travel of the carriage to a contracted position within said frame.

7. In a typewriting machine, the combination of a frame or case having a door in one side thereof, a carriage, means whereby said 25 carriage may be moved from its normal operative position to a contracted position within said case and through the door opening therein, and a cover which closes the top of the frame and with the frame and door encloses the entire machine when the 30 carriage is moved into the frame.

8. In a typewriting machine, the combination of a frame or case having a bottom and fixed rear and side walls with a door in one 35 of the latter, a carriage, means whereby said carriage may be moved from its normal operative position to a contracted position within said case and through the door opening therein, and a cover which closes the 40 top of the frame and with the frame and door encloses the entire machine when the carriage is moved into the frame.

9. In a typewriting machine, the combination of a frame or case having a bottom and fixed rear and side walls with a door in one 45 of the latter, a carriage supported in its operative position above said case and adapted to travel over the same and beyond the side walls thereof, means which enable said carriage to be moved from its position of 50 use into said frame or case and through the

door opening therein, and a cover which closes the top of the frame and with the frame and door encloses the entire machine when the carriage is moved into the frame. 55

10. In a typewriting machine, the combination of a frame or case having a bottom and fixed rear and side walls with a door in one of the latter, a carriage supported in its operative position above said case and 60 adapted to travel over the same and beyond the side walls thereof, means which enable said carriage to be inverted, lowered and introduced through the door opening into the frame of the machine, and a cover which 65 closes the top of the frame and with the frame and door encloses the entire machine when the carriage is moved into the frame.

11. In a typewriting machine, the combination of a main frame, a carriage, a carriage-support swingable laterally upside down beyond one side of the main frame, and means whereby said carriage and its support may then be moved longitudinally 70 inside the main frame. 75

12. In a typewriting machine, the combination of a main frame, an auxiliary frame having longitudinal tracks continuing at one end vertically and then terminating in horizontal seats, a carriage, and a carriage-bed having pins adapted to said seats and to travel on said tracks, whereby the carriage and carriage-bed may be turned upside down and housed within the main frame. 80 85

13. In a typewriting machine, the combination of a main frame, a carriage, a carriage-support pivotally supported at one end so that it may be turned laterally through substantially 180°, and guideways 90 in the main frame for enabling the carriage-support and the carriage to be slid endwise within the main frame and there held while the machine is in disuse.

Signed at Boston, in the county of Suffolk and State of Massachusetts this 14th day of January, A. D. 1920. 95
